FIG. 1 is a perspective view of a color coded nozzle showing our new design;

FIG. 2 is a view taken from the discharge end thereof;

FIG. 3 is a view taken from the inlet end thereof;

FIG. 4 is a side elevational view thereof;

FIG. 5 is a perspective view of a modified form of the color coded nozzle as shown in FIG. 1;

FIG. 6 is a view taken from the discharge end of FIG. 5;

FIG. 7 is a view taken from the inlet end of FIG. 4;

FIG. 8 is a side elevational view of FIG. 5;

FIG. 9 is a perspective view of a second modified form of the color coded nozzle as shown in FIG. 1;

FIG. 10 is a view taken from the discharge end of FIG. 9;

FIG. 11 is a view taken from the inlet end of FIG. 9; and

FIG. 12 is a side elevational view of FIG. 9.

The dominant feature of our design resides in the contrasting color collar on the discharge end thereof.

We claim:

The ornamental design for a color coded nozzle, as shown and described.
